UNITED STATES PATENT OFFICE.

EUGÈNE SCHNEIDER, OF LE CREUZOT, FRANCE, ASSIGNOR TO SCHNEIDER & CIE., OF PARIS, FRANCE, A LIMITED JOINT-STOCK COMPANY OF FRANCE.

DOOR FOR THE EXIT OF TORPEDOES LAUNCHED FROM TORPEDO-TUBES.

1,310,880.

Specification of Letters Patent.

Patented July 22, 1919.

Application filed May 15, 1917. Serial No. 168,856.

To all whom it may concern:

Be it known that I, EUGÈNE SCHNEIDER, a citizen of the Republic of France, residing at Le Creuzot, Saône-et-Loire, France, have 5 invented a new and useful Improvement in or Relating to Doors for the Exit of Torpedoes Launched from Torpedo-Tubes, which is fully set forth in the following specification:

10 In vessels carrying torpedoes, and more particularly in submarines and submersible vessels, the torpedo tubes are often fixed and wholly contained inside the hull or structure. In such a case the launching of the 15 torpedoes requires the opening of the cover that closes directly the exit end of the torpedo tube, and also the moving out of the way of a door or shutter or movable caisson which is formed, according to the circumstances, either in the hull or in the superstructure of the vessel, and which when normally closed, insures the continuity of the 20 lines of the said hull or superstructure.

In the known arrangements of this kind 25 and particularly when they are employed in combination with torpedo tubes directed toward the stem of the vessel, doors are provided in the hull of the vessel hinged on vertical axles; they are approximately parallel 30 to the stem, and for the purpose of launching the torpedo, they are adapted to move out of the way, in most cases into the interior, that is to say, toward the central vertical longitudinal plane of the vessel.

35 If, as is generally the case, the torpedo tubes in the stem are arranged symmetrically to the central vertical longitudinal plane of the vessel, the known system above referred to does not allow of arranging the tubes 40 symmetrically side by side, for the reason that it is necessary to provide in the central vertical plane between the two adjacent tubes, accommodation for the two doors in their open positions.

45 Further, the doors which are pivoted to the stem and are adapted to move out of the way, that is to say, to open into the central vertical longitudinal plane of the vessel, should for the same height have a greater 50 length, because in order to fine off the shape of the forepart of the vessel, the exit end of the tube is shifted farther aft. In this case the door support which is arranged along an extreme vertical edge of the door aper-

ture, becomes then insufficient, and the door, 55 as well as its hinges, are subjected to excessive strains. Moreover, if the shape of the hull at the place which is to be cut for the doors, comprises complex curves, great difficulty will be experienced in hinging the 60 doors, and they will take up still more room when opened.

Those drawbacks are now done away with by the present invention, according to which the exit doors provided in the hull or in the 65 structure opposite the covers of the corresponding torpedo tubes, are movable on horizontal or approximately horizontal axles, extending approximately along the flow 70 lines of the hull or superstructure at the apertures provided for the passage of the torpedoes. This improved principle of construction which also allows in a very simple manner of combining the opening and closing movements of each door with the 75 corresponding movements of the corresponding torpedo tube cover, affords the following advantages:

1. It allows of fineing off the lines of the forepart of the vessel: 80

a. By arranging the torpedo tubes as near to the central vertical longitudinal plane of the vessel as the actual construction of these tubes will allow. As a matter of fact there is no necessity for providing between the 85 prolongation of the two tubes, accommodation for any part of the doors, because the latter may be adapted to open toward the outside of the vessel if necessary.

b. By arranging the end of the tubes farther away from the stem and lengthening the doors for which it is easy to provide always a good bearing upon their rotational axles, since the latter are parallel to the long horizontal dimension of the doors, which dimension alone increases with the distance of the tubes from the stem, while the height of the doors remains constant. Consequently the axles can be connected to their doors and to the shell plating for as long a length as 100 desired, thereby doing away with all strain upon the said doors. 95

2. It facilitates the adaptation of a door to hulls which have very curved lines at the place where this door is desired to be provided. 105

Finally, instead of fixing the device for actuating the door, to the body of the door,

the said device may be fixed to the axle of the door hinges, whereby greater rigidity is assured.

The manner in which this invention is to be performed will now be more particularly described with reference to the accompanying drawings which illustrate by way of example a practical construction of apparatus according to this invention.

10 In these drawings:

Figure 1 is a perspective elevation partly in section of a general arrangement of a door constructed according to this invention in combination with a torpedo tube arranged wholly inside the hull of a submarine or other vessel. This figure shows also the mechanism connecting the said door to the cover that closes the fore end of the tube.

Fig. 2 is a horizontal section on the line 20 II-II of Fig. 1.

Fig. 3 is a vertical section on the line III-III of Fig. 2.

Fig. 4 is a vertical section similar to that of Fig. 3; it illustrates a modified form of 25 the door.

Figs. 5, 6 and 7 are respectively a perspective elevation, a plan, and a vertical section on the line VII-VII of Fig. 6, illustrating the application of the invention in combination with a torpedo tube arranged wholly 30 inside the superstructure of a submarine or other vessel.

In the example shown in Figs. 1 to 4 inclusive, the installation is assumed to comprise two sets of the improved apparatus arranged symmetrically to the central vertical longitudinal plane of the vessel.

In these figures, A is the torpedo tube the fore end of which projects out through 40 a partition B, and may, as shown in Fig. 2, be situated very close to the stem C without the opening of the doors interfering in any way with the fineness of the lines of the forepart of the vessel.

45 D indicates the contour of the aperture formed in the side of the vessel; this aperture which is normally closed by the door E is entirely uncovered by the opening of the door for the launch of the torpedo. This 50 opening of the door must allow an entirely free passage for the curves of the torpedo outside the vessel.

The door E is hinged in all cases directly or by means of suspension arms, in such a 55 manner as to be capable of turning with axle e extending approximately parallel to the horizontal sections of the hull plating at the corresponding part of the vessel.

In the examples shown in Figs. 1 to 4, 60 the axle e is arranged in such a manner as to allow of the door opening toward the outside of the vessel. This axle which is not limited in length by the height of the door, may be arranged in all cases as closely as desired to the longitudinal edge of the door,

without this position being determined by the necessity for moving the door out of the way and of the space taken up by the door when so moved out of the way.

As shown, the axle may be mounted on 70 the hull plating or journaled in bearings e¹ fixed to the latter. In this case it is rigidly connected to the door E by means of hinge straps e² or other equivalent devices.

In the example shown in Figs. 5 to 7 75 illustrating the improved apparatus in combination with a torpedo tube contained in the superstructure of a vessel, the hinge axle of the door is arranged below the latter and below the path of the torpedo, and the door 80 is arranged to open toward the inside of the vessel.

In the modification shown in Fig. 4, the door E has a lens-like shape which allows of reducing as much as possible its resistance to the progress and rolling motion of 85 the vessel when it is moved into its open position as indicated in dot and dash lines.

The moving of the door out of the way is effected in all cases in the known manner by means of mechanism which is actuated preferably in connection with the actuating mechanism of the cover F of the tube A; but, contrary to that which takes place in the known arrangements, the part actuating the door may, according to the present invention, be fixed on the hinge axle of the door. The mechanism comprises a toothed sector e³ fixed on the axle e and engaging a worm G journaled in a suitable bracket H. 100 The spindle of this worm G carries a bevel wheel g engaging a pinion i carried by an axle I journaled in the bracket H. A Cardan-joint gearing J—j—j¹ connects the axle I to the shaft K that carries the worm L 105 actuating the cover F.

The mere actuation of the shaft K allows of operating simultaneously the door E and the cover F through the medium of the described gearing. The cap F is preferably mounted in the manner described in Laubef's French Patent, No. 403991 of 7th October 1908; it is jointed at its center to an axle f carried by an arm M, fixed on an axle m journaled in a bracket a fixed to the 110 side of the tube A. On the axle m there is fixed a toothed sector N engaging the worm L.

Having now described my invention, what I claim as new and desire to secure by Letters Patent is:

1. In combination, a boat provided with a torpedo tube and having a torpedo exit opening in the side thereof, a closure for said opening provided with a substantially 125 horizontal axle fast thereto, said axle having approximately the direction of the flow lines of the hull of the boat.

2. In combination, a boat provided with a torpedo tube and having a torpedo exit 130

opening in the side thereof, a closure for said opening provided with a substantially horizontal axle fast thereto, said axle having approximately the direction of the flow lines of the hull of the boat, and provided with a gear member and door-operating means adapted to engage said gear member.

3. In combination, a boat provided with a torpedo tube having a hinged cover, said boat having a torpedo exit opening in the side thereof, a closure for said opening provided with a substantially horizontal axle

fast thereto, said axle having approximately the direction of the flow lines of the hull of the boat, and a common means for operating 15 said cover and said door axle.

In testimony whereof I have signed this specification in the presence of two subscribing witnesses.

EUGÈNE SCHNEIDER.
